Primary Examiner — Karen E Eldridge Powers*(74) Attorney, Agent, or Firm* — Wayne IP LLC(57) **CLAIM**

The ornamental design for a retractable needle comb, as shown and described.

DESCRIPTION

FIG. 1 is a front, top and right side perspective view of a retractable needle comb showing my new design; FIG. 2 is a back, bottom and left side perspective view thereof.

FIG. 3 is a front elevational view thereof;

FIG. 4 is a back elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings illustrate portions of the retractable needle comb that form no part of the claimed design.
